UNITED STATES PATENT OFFICE.

JAMES M. IDE, OF TROY, NEW YORK, ASSIGNOR TO GEORGE P. IDE, BRUCE & CO., OF SAME PLACE.

COMBINED RE-ENFORCE AND STAY FOR THE BACKS OF SHIRTS.

SPECIFICATION forming part of Letters Patent No. 313,870, dated March 17, 1885.

Application filed April 7, 1884 (No model.)

To all whom it may concern:

Be it known that I, JAMES M. IDE, of the city of Troy, county of Rensselaer, State of New York, have invented a new and useful 5 Improvement of a Combined Re-Enforce and Stay for the Backs and Back-Openings of Shirts, of which the following is a specification.

My invention relates to improvements in 10 that class of shirts that are made with a back re-enforce at each side of the slit, and which re-enforce parts are also employed to produce a stay for the back-slit, the object of my invention being to give a good finish to the parts, 15 and to more securely connect them by forming one of the re-enforce parts or pieces wider and longer than the other, so that where it is wider it will subtend the edge of the slit to form an overlap thereat, and where longer a tab- 20 stay at the bottom of the slit, with the vertical edge of the narrower width re-enforce piece having its edge coincident with the edge of the slit, and the two re-enforce parts thus cut combined with a separate strip that is attached to 25 form the inner facing of the overlapping part of the re-enforce, and the outer facing of that other part of the re-enforce which, with the edge of the slit beneath it, forms the underlap.

Accompanying this specification and forming 30 a part of it there are three plates of drawings containing four figures illustrating my invention, with the same designation of parts by letter reference used in all of them.

Of these illustrations, Figure 1 shows a part 35 of a shirt-back with my invention applied thereto, with the button-fly or overlap illustrated as turned outwardly at the top of the garment-slit. Fig. 2 shows a cross-section 40 taken on the line xx of Fig. 1, with the thickness of the parts somewhat exaggerated to better illustrate them. Fig. 3 shows a shirt-back with the two-part re-enforce in part attached to the latter, with the lower end of that part of 45 the re-enforce cut to produce the overlap turned out to illustrate its attachment to a facing-strip used in connection with a two-part re-enforce to produce the inner facing of the overlap and the outer facing of the underlap, the said strip being shown as turned out 50 at the top of the slit to illustrate the attach-

ment. Fig. 4 illustrates the two-part re-enforce and the facing-strip as sewed to that edge of the re-enforce part cut to produce the overlap, with the end of said strip shown as 55 turned up.

The several parts of my invention and those of a shirt with which it connects are designated by letter reference and their attachment is described as follows:

The letters A' and A'' indicate the two parts of the re-enforce. The part designated at A' is cut wider and a little longer than the other, so that on the side of its greatest length it can overlap the edge of the garment, and extend 65 below the bottom of the slit when attached thereto, as will be subsequently described.

The letters B designate the shirt-back, and F the facing-strip; O' , the completed overlap, and O'' the underlap, the letter T indicating 70 the lower portion of that part of the re-enforce A' cut wider than the other part to form the facing for the overlap, said part T extending below the slit M , to be secured to the garment thereat to form a stay.

The parts thus cut and described are attached as follows: The strip F is first sewed at a' on one of its edges to the vertical edge of the re-enforce part A' , as indicated at Fig. 4, and then said strip F is on its opposite edge 80 sewed to the adjacent edge of the slit, as indicated at a'' , and in continuity sewed to the coincidently laid edges of the re-enforce part A'' and the remaining unattached edge of the slit M . When this has been done, that part of 85 the strip forming the underlap is folded over and down, and sewed to the re-enforce part A'' and shirt at d' , and the overlapping part A' is sewed to the strip, as indicated at d'' , with the tab end T , border-sewed to the shirt-back 90 below the slit, and cross-sewed at the bottom of the slit, as designated at a'' . The re-enforce parts A' and A'' are each sewed to the shirt-back, as designated at e' e'' , and where adjoining the sleeve they are at each side sewed into the seam, uniting the sleeve with the shirt, as indicated at D' D'' , that part of the sleeve where thus attached being designated at N . At the top of the shirt the re-enforce parts may be attached at or below the yoke-seam, 95 and where joining the sleeve-seam the re-enforce parts A' and A'' may be cut deeper, so

as to be included in the sleeve-seam as far around on the lower part of the latter as the side seam of the shirt, if desired.

A shirt thus made has a re-enforce attached where its use is very advantageous, and as made it can be applied to produce an overlap for the back-opening of the shirt, both of which features can be attached to the shirt by the same operation.

10 Having thus described my invention, what I claim, and desire to secure by Letters Patent, is—

15 1. In a combined re-enforce and stay for the back-slit of shirts, the combination of the re-enforce part A', attached to the shirt-body at e', and cut to overlap one edge of and the bottom of the slit, and attached to the shirt below the latter, the re-enforce part A², attached to the shirt-body at e², having its vertical edge 20 parallel with the adjacent side of the slit where underlapping said part A', and the strip F, attached to the inner facing of the overlapping part of the re-enforce, and to the outer

face of the underlap of the said part A² and the shirt beneath the latter, as shown and described.

2. In a shirt-back, the combination of the slit M, the overlap O', produced on and by the lateral subtension of the vertical edge of the re-enforce part A', the underlap O², produced by the vertical edge of the re-enforce part A² and the shirt-body at the edge of the slit beneath said last-named re-enforce part, and the strip F, attached to the inner face of said overlap and the outer face of the underlap and shirt beneath it thereat, as shown and described.

Signed at Troy, New York, this 31st day of March, 1884, in the presence of the two witnesses whose names were by them hereto written.

JAMES M. IDE.
